SHEET METAL PISTON MANUFACTURE

George M. Ambrosius, Lakewood, Ohio, assignor
to The Standard Oil Company (Ohio), Cleve-
land, Ohio, a corporation of Ohio

Application May 25, 1936, Serial No. 81,665

7 Claims. (Cl. 153—73)

This invention, relating to sheet metal ware manufacture, has more particular reference to the production of metallic structures on the order of pistons such as for grease cartridges, etc.; and it is among the objects of the invention to facilitate accurate manufacture of such articles. Other objects and advantages will appear as the description proceeds.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative however, of but a few of the various ways in which the principle of the invention may be employed.

In said annexed drawings:—

Fig. 1 is a vertical sectional view of die mechanism contemplated in the invention; Fig. 2 is a plan view thereof; Fig. 3 is a section corresponding to Fig. 1, showing the parts in closed position; and Fig. 4 is a transverse section taken on a plane substantially indicated by line IV—IV, Fig. 1.

In an assemblage of die elements, as indicated in Fig. 1, etc., die blocks 2, 3, are arranged for reciprocatively opposed motion so as to close together and be separated by some suitable means, as for instance a reciprocating press, mechanical or hydraulic, the respective die blocks being secured to the jaws P thereof. Fixed to one of said die blocks, 3, is a central stud 5, having a cylindrical body portion 6 and a taper cam portion 8. The stud may be secured to the die block by suitable means, for instance screws 7. About the stud and reciprocable thereon is a follower plate 9 capable of a limited excursion of movement, being urged in a direction away from the block by spring means 10. To limit the movement of such follower plate, a shoulder retaining means or ring 11 slightly overhanging the plate, is suitably secured to the die block 3, such as by screws 12. On the follower plate is an inner set of radially movable die sections 13 having raised central portions 14 with die surfaces peripherally thereon. The movable die sections 13 are actuated by suitable means, for instance conveniently the taper cam 8, whereby to force them outwardly and bring into action the peripheral dieing surfaces of the portions 14. Coacting with such die surfaces is an outer set of radially movable die sections 15, these being reciprocatively mounted, conveniently on the die sections 13, and having spring means 16 therebetween, as in recesses, for

normally separating the inner and outer die sections. A suitable retaining means or guide, as retaining ring 17 prevents disassembly, while permitting radial reciprocating movement of the die sections 15. On the outer ends of the die sections 15 are cam or beveled surfaces 18, and the other die block 2 carries an actuating cam therefore, such as cam ring 20, internally beveled as at 21 to coact with the cam surfaces 18 when forced thereagainst. The actuating cam 20 is suitably secured to the die block 2, as by screws 22. From the structure this far it is seen that when the die blocks 2 and 3 are forced into apposition by the press the cam 20 riding onto the cam ends 18 of the outer set of die sections 15 forces them inwardly, and at the same time the cam 8 forces the inner die sections outwardly into action.

Within the cam ring 20 is a follower ring 25, and this is normally urged away from the die block by suitable means, as springs 26, and limited in its movement away from the die block, for instance by limit-screws with heads moving in limiting-bores, as shown in dotted outlines in Fig. 3, beyond the springs 26. Centrally of the follower ring 25 is a center follower 27 having a blank-engaging center stud 28. This follower is also normally urged away from the die block by suitable means, as spring means 30. To properly limit the range of motion of the center follower, 30 a shouldered retaining means or ring 31 is arranged in relation, and held to the die block by suitable means, as screws 32.

With the press, ready for operation, and the dies in position as in Fig. 1, a sheet metal blank 35 is fed into the die cavity by suitable means, hand feed or automatic, the detail being immaterial here, and with the closing of the dies, the coacting die surfaces shape and true the sheet metal blank to final finished form F shown in Fig. 3. With 40 the separation or opening of the dies, the sheet metal piece or formed piston is free, and is discharged suitably, manually or by an air blast through an air duct a in the die block 3. A new blank is fed, and the operation repeated.

Other modes of applying the principle of the invention may be employed, change being made as regards the details described, provided the features stated in any of the following claims, or the equivalent of such, be employed.

I therefore particularly point out and distinctly claim as my invention:—

1. In die mechanism of the character described, reciprocatively opposed die blocks, a central stud fixed to one of said blocks having a cylindrical

body and taper cam, a follower plate reciprocable on such stud, spring means tending to thrust said follower plate away from said block, a shouldered retaining ring for limiting movement of said follower plate, an inner set of radially movable die sections on said follower plate to be spread by said taper cam and having raised central portions with peripheral die surfaces, an outer set of radially movable die sections on said inner die sections, beveled cam surfaces on the outer ends of said outer die sections, spring means tending to separate the outer and inner die sections, a retaining ring for holding said outer die sections against disassembly, an internally beveled cam ring carried by the other of the first-mentioned opposed die blocks adapted to coact with the beveled cam surfaces on the outer ends of said outer die sections, a follower ring carried by the same die block internally of said cam ring, spring means normally urging said follower ring from the die block, a center follower carried by the same die block and having a blank-engaging center stud, spring means normally urging said center follower from the die block, and a shouldered retaining ring on the die block for limiting the movement of said center follower.

2. In die mechanism of the character described, reciprocatively opposed die blocks, a central stud fixed to one of said blocks having a cylindrical body and taper cam, a follower plate reciprocable on such stud, spring means tending to thrust said follower plate away from said block, a shouldered retaining ring for limiting movement of said follower plate, an inner set of radially movable die sections on said follower plate to be spread by said taper cam and having raised central portions with peripheral die surfaces, an outer set of radially movable die sections on said inner die sections, beveled cam surfaces on the outer ends of said outer die sections, means for separating the outer and inner die sections, a retaining ring for holding said outer die sections against disassembly, an internally beveled cam ring carried by the other of the first-mentioned opposed die blocks adapted to coact with the beveled cam surfaces on the outer ends of said outer die sections, a follower ring carried by the same die block internally of said cam ring, spring means normally urging said follower ring from the die block, a center follower carried by the same die block and having a blank-engaging center stud, spring means normally urging said center follower from the die block, and a shouldered retaining ring on the die block for limiting the movement of said center follower.

3. In die mechanism of the character described, reciprocatively opposed die blocks, a central stud fixed to one of said blocks having a cylindrical body and taper cam, a follower plate reciprocable on such stud, spring means tending to thrust said follower plate away from said block, a shouldered retaining ring for limiting movement of said follower plate, an inner set of radially movable die sections on said follower plate to be spread by said taper cam and having raised central portions with peripheral die surfaces, an outer set of radially movable die sections on said inner die sections, means for separating the outer and inner die sections, a retaining ring for holding said outer die sections against disassembly, cam means carried by the other of the first-mentioned opposed die blocks to operate said outer die sections, a follower ring carried by the same die block internally of said cam ring, spring means normally urging said follower ring from the die block.

the die block, a center follower carried by the same die block and having a blank-engaging center stud, spring means normally urging said center follower from the die block, and a shouldered retaining ring on the die block for limiting the movement of said center follower.

4. In die mechanism of the character described, reciprocatively opposed die blocks, a central stud fixed to one of said blocks having a cylindrical body and taper cam, a follower plate reciprocable on such stud, spring means tending to thrust said follower plate away from said block, a shouldered retaining ring for limiting movement of said follower plate, an inner set of radially movable die sections on said follower plate to be spread by said taper cam and having raised central portions with peripheral die surfaces, an outer set of radially movable die sections on said inner die sections, means for separating the outer and inner die sections, a retaining ring for holding said outer die sections against disassembly, cam means carried by the other of the first-mentioned opposed die blocks to operate said outer die sections, a follower ring carried by the same die block internally of said cam ring, a center follower carried by the same die block and having a blank-engaging center stud, and a shouldered retaining ring on the die block for limiting the movement of said center follower.

5. In die mechanism of the character described, reciprocatively opposed die blocks, a central stud fixed to one of said blocks having a cylindrical body and taper cam, a follower plate reciprocable on such stud, spring means tending to thrust said follower plate away from said block, a shouldered retaining ring for limiting movement of said follower plate, an inner set of radially movable die sections on said follower plate to be spread by said taper cam and having raised central portions with peripheral die surfaces, an outer set of radially movable die sections on said inner die sections, means for separating the outer and inner die sections, a retaining ring for holding said outer die sections against disassembly, cam means carried by the other of the first-mentioned opposed die blocks to operate said outer die sections, a follower ring carried by the same die block internally of said cam ring, a center follower carried by the same die block and having a blank-engaging center stud, and means for limiting the movement of said center follower on the die block.

6. In die mechanism of the character described, reciprocatively opposed die blocks, a central stud fixed to one of said blocks having a cylindrical body and a taper cam, a follower plate reciprocable on said stud, means for limiting the movement of said follower plate, an inner set of radially movable die sections on said follower plate to be spread by said taper cam and having central portions with peripheral die surfaces, an outer set of radially movable die sections on said inner die sections, means for separating the outer and inner die sections, means for retaining said outer die sections against disassembly, cam means carried by the other of the first-mentioned opposed die blocks to operate said outer die sections, a follower ring carried by the same die block, a center follower also carried by the same die block and having a blank-engaging center stud, and means for limiting the movement of said center follower.

7. In die mechanism of the character described, reciprocatively opposed die blocks, a follower plate reciprocable on one of said die blocks, means for limiting the movement of said follower

plate, an inner set of radially movable die sections on said follower plate having central portions with peripheral die surfaces, self-contained means for spreading said inner set of die sections, 5 an outer set of radially movable die sections on said inner die sections, means for retaining said outer die sections against disassembly, a center

resiliently-urged blank-engaging follower carried by the other of the first-mentioned opposed die blocks, a follower ring about said center follower, and cam means carried by the same die block to operate said outer die sections. 5

GEORGE M. AMBROSIUS.
